CLAIM

The ornamental design for a separating device, as shown and described.

DESCRIPTION

FIG. 1 is a top perspective view of a separating device showing our new design;

FIG. 2 is a top plan view of the separating device shown in FIG. 1;

FIG. 3 is an elevational view of one side of the separating device shown in FIG. 1, the other side being a mirror image thereof;

FIG. 4 is an elevational view of one end of the separating device shown in FIG. 1;

FIG. 5 is an elevational view of the other end of the separating device shown in FIG. 1;

FIG. 6 is a bottom plan view of the separating device shown in FIG. 1;

FIG. 7 is a top perspective view of a separating device showing a second embodiment of our new design; and,

FIG. 8 is a top plan view thereof. The side, end, and bottom views of the second embodiment are identical to that of the first embodiment.
